UNITED STATES PATENT OFFICE

2,435,582

MACHINE FOR USE IN ATTACHING SOLES
TO SHOESHelge Gulbrandsen, Beverly, Mass., assignor to
United Shoe Machinery Corporation, Flemington, N. J., a corporation of New Jersey

Application September 29, 1944, Serial No. 556,333

13 Claims. (Cl. 12—1)

1

This invention relates to machines for cement-attaching soles to shoes, and particularly to apparatus operated thereby for handling a shoe and its sole prior to attachment and for presenting them to the operator at the proper time for placing them together under pressure in a sole-attaching machine.

Objects of the invention are to facilitate the practice of the method disclosed in United States Letters Patent No. 2,373,922, granted April 17, 1945, upon an application of Max W. Tetlow.

The illustrated machine provides improved apparatus comprising a cabinet for treating at one time a plurality of soles with hot vapor-laden air both to temper the soles and to activate the cement thereon, the cabinet being, as illustrated, arranged adjacent to a sole-attaching machine of the eight-station turret type similar to that disclosed in Letters Patent of the United States No. 2,047,185, granted July 14, 1936, on application of Milton H. Ballard et al.

Means operated by rotation of the turret of the sole-attaching machine is provided for ejecting soles from the cabinet one after the other, and a supplementary carrier or turntable having a plurality of trays for holding the shoes is provided, this carrier being arranged to be rotated one stage at each indexing of the turret of the machine to present a shoe to which the ejected sole is to be attached.

The arrangement is such that, after the cabinet has been heated up, several soles placed in the cabinet and a corresponding number of shoes placed in the trays, at each indexing of the machine a sole will be ejected from the cabinet and the shoe to which it is to be attached will be presented by the adjacent tray. The operator will, of course, supply a new sole to the cabinet in place of the sole last ejected and a new shoe in a vacant tray of the turntable.

The rate of operation of the machine is usually such that the turret is indexed about every ten seconds, whereas a sole, in order for the cement thereon to be properly activated and the sole put in temper to render it inert, should remain in the cabinet for from thirty to forty seconds. Accordingly, the cabinet is arranged to hold four soles at a time, and five trays are provided on the turntable so that there will be a vacant tray to receive a shoe before the one presented for attachment is removed from its tray.

These and other features of the invention will appear more fully from the following description when read in connection with the accompanying

2

drawings and will be pointed out in the appended claims.

In the drawings,

Fig. 1 is a front view in perspective of a so-called eight-station sole-attaching machine of the type disclosed in the Ballard et al. patent above referred to, equipped with the apparatus of the present invention, the pad, gages and pressure-applying mechanism at the operating station being shown in full, and the two adjacent identical pads, gages and pressure-applying mechanisms being shown in outline;

Fig. 2 is a plan view of the activating cabinet and the shoe carrier or turntable mounted on a sole-attaching machine of the type referred to;

Fig. 3 is a front elevation of the activating cabinet and the shoe-carrying turntable;

Fig. 4 is a longitudinal sectional view of the cabinet showing the sole-ejecting mechanism;

Fig. 5 is a plan view of the sole-holding rack with which the cabinet is provided;

Fig. 6 is a plan view of the cabinet with the cover raised;

Fig. 7 is a sectional detail showing the connections for supplying water to the base of the cabinet and maintaining a constant level of water therein;

Fig. 8 is a rear elevation of the sole-ejecting mechanism;

Fig. 9 is a perspective view of parts shown in Fig. 7; and

Fig. 10 is a plan view of the air and water pumps at the base of the machine.

Referring to Figs. 1 and 2, the numeral 10 indicates a shaft about the center of which the turret 250 of the sole-attaching machine rotates, several of the cylinders carried by the turret and by which pressure is applied to the shoe and sole being shown at 12 (Fig. 2). A shoe-carrying turntable 14 (Fig. 3) has a hub 16 which is journaled in a stud 18 mounted in a bracket 20 fixed at one end to the shaft 10 at the center of the turret of the machine and at the other end to a shelf 24 on which an activating cabinet 26 is mounted. The turntable 14 and the cabinet 26 are arranged at about breast height so the operator can conveniently reach them.

On the turntable 14 are five blocks 30 having surfaces 32 downwardly and outwardly inclined at about 30° to the horizontal and to each of these surfaces are attached curved strips 34 arranged to form a tray to receive a shoe. The cabinet 26 is an improvement over that disclosed in Letters Patent of the United States No.

2,334,232, granted November 16, 1943, upon the application of Adoniram J. Wells. The cabinet 26 consists of a metallic casing 40 (Fig. 4) preferably covered with a thick layer of insulating material 42 and having a hinged cover 44 held closed by a screw 46. In the cover is a chimney 48 having a damper 50 to control ventilation through the chimney. In the front of the casing (Fig. 3) is a series of four slots 51, 52, 53 and 54 through which soles O may be introduced into the upper part of the cabinet toe end first.

The soles are supported on their edges in a removable cage comprising an upper rectangular frame 60 (Fig. 4) and a similar lower rectangular frame 62, the frames being connected at their ends by vertical struts 64. Arranged longitudinally of the frames and supported at their ends in the struts 64 are dowel-like rods 66 (Fig. 5) of non-heat-conducting material such as wood arranged to form four stalls 71, 72, 73 and 74 to receive soles, the front ends of the stalls being positioned opposite the slots in the casing. As indicated in Fig. 4, each side of each stall is formed by four of the rods 66 supported at their ends in the vertical struts 64.

The edges of the foreparts of the soles rest on a series of transverse rods 76 supported at their ends in the lower frame 62 and the rear ends of the soles rest on a wire mesh 78 which facilitates sliding of the soles lengthwise of the stalls. The frame 62 of the cage rests on screw studs 80 projecting inwardly of the casing and is held in place by hooks 82 engaging the sides of the upper frame 60 and serving to hold the cage from lateral movement with the stalls alined with the slots.

In front of the slots (Figs. 1 and 3) is a canvas curtain 84 which covers the upper parts of the slots, the curtain being slit at 86 centrally of the slots and the edges bound with durable flexible material such as leather. The soles are readily insertable into the cabinet through the slits in the curtain.

Compressed air is supplied by a pipe 90 entering through the side of the cabinet (Fig. 6) connected first to a pipe 92 extending around the periphery of the cabinet near the wall and below the soles. The pipe 90 is perforated at intervals in its upper side by holes 94 which allow air to pass upward into the sole-treating chamber. The pipe 90 is connected to a vertical pipe 96 (Fig. 4) having therein a restricted passage 98 which allows part of the air to pass to a series of connected pipes 100 which are perforated on their lower sides and are partially immersed in water contained in the lower part of the cabinet. The water level is indicated at 102 (Fig. 7), and running lengthwise of the bottom of the cabinet is a depression or well 104 (Fig. 3) in which is an immersion heater 106 supplied with current from a junction box 108 on which is a light 110 which glows when the current is on. The current is controlled by a thermostat 112 which is adjusted to maintain the water at a predetermined temperature by turning a knob 114, the setting being indicated by movement of a pointer 116 over a temperature scale 118. The temperature of the vapor-laden air in the cabinet is indicated by a thermometer 120 located (Fig. 4) a short distance below the pipe 92.

Between the pipe 92 and the thermometer 120 is a solid baffle plate 122 which extends nearly to the walls of the cabinet but is spaced therefrom at 124 (Fig. 6) enough to allow circulation of the vapor-laden air around its edges up into

the sole-treating chamber. Spaced downwardly from the baffle plate 122 is another plate 126 which has a large piece removed from its rear end, as indicated by the line 128. Below the plate 126 is a third plate 130 which is perforated throughout its extent by relatively large holes 132. These baffles insure that any water in a liquid state will be removed from the hot vapor-laden air before it reaches the sole-treating chamber.

Compressed air is supplied to the pipe 90 by an air pump 140 (Fig. 10) located in the base of the machine and driven by a belt 142 from a suitable motor. The air enters the pump through a suitable strainer 144 and is discharged through the pipe 90 which extends up to the cabinet through a protective casing 146. The pump 140 is supplied with oil by an oil cup 148.

Water is supplied to the bottom of the casing 40 by a rotary pump 150 driven by a belt 152 from the air pump 140. The pump 150 receives water through a pipe 154 from a tank 156 and delivers it through a pipe 158 to a chamber 160 (Fig. 7) formed by a pocket 162 secured by screws 163 to the side of the cabinet casing 40 and having a cover 164. An outlet pipe 166 enters the chamber 160 at a slightly higher level than the inlet pipe 158 and conducts the excess of water back to the tank 156. Leakage through the bearing of the pump 150 is led back to the tank by a pipe 168 (Fig. 10). The pipes 158 and 166 also pass up through the protective casing 146.

The capacity of the water pump 150 is such that the chamber 160 is continuously supplied with cool water and maintained at a substantially constant level by the overflow pipe 166. Communication between the chamber 160 and the lower part of the casing 40 is provided by a small opening 170 (Fig. 7) so that, as the heated water in the casing 40 evaporates, its place will be taken by cool water from the chamber 160 and the level of water in the casing maintained constant. The opening 170 is preferably made by providing a groove in the side of a plug which fits a larger opening and can be removed for cleaning if necessary.

Soles placed in the cabinet for tempering and activation of the cement thereon are ejected serially by mechanism best shown in Figs. 2, 4, 8 and 9. A series of rods 171, 172, 173 and 174 project through openings 176 in bosses 178 from the rear end of the casing 40. Each boss is counterbored (Fig. 4) to receive a rubber washer 180 which is held in place by a plate 182, the washers sealing the opening but permitting silent reciprocation of the rods therethrough. At the rear end of each of the stalls 71, 72, 73 and 74 is a pusher 184, the pushers being attached one to each of the rods 171, 172, 173 and 174, and each acting when its rod is reciprocated to engage the front end of the sole O and push the heel end out of the slot in the front end of the casing far enough so that it can be easily grasped by the operator.

The rods 171, 172, 173 and 174 are reciprocated in turn by the following mechanism: Each rod projects through a block 190 in which it is adjustably secured by a setscrew 192. Each block is pivoted at 194 to a lever, the levers being numbered 201, 202, 203 and 204 (Fig. 8) in the order of the rods. The levers are all pivoted on a shaft 206 mounted in a bracket 208 secured at 210 to the shelf 24 which supports the cabinet. Each lever has a lower arm 212 to which

a tension spring 214 is attached, the front end of the spring being secured to an ear 216 on the bracket 208. The tension of the spring holds each lever turned clockwise (Fig. 4) until a projection 218 thereon rests against a stop screw 220 threaded through a portion 222 of the bracket 208.

To operate the levers 201, 202, 203 and 204 in sequence, for example in the order in which they are numbered, a shaft 224 is journaled in bearings 226, 228 formed on the bracket 208 (Fig. 8). At one side of the bearing 228 a collar 230 is pinned on the shaft 224 and at the other side of the bearing is pinned an eight-toothed ratchet wheel 232 (Fig. 4) counterclockwise movement of which is prevented by a leaf spring 234 formed as a pawl engaging the ratchet and secured at 236 to the bearing 228. On the shaft 224 (Figs. 8 and 9) is a series of double-ended tappets 241, 242, 243 and 244 so arranged rotationally on the shaft that when the shaft is given a partial rotation one-eighth of a turn the tappet 241 will engage the arm 212 of the lever 201 and will operate the pusher on the rod 171 to eject the sole in the stall 71 through the slot 51. The next partial rotation of the shaft 224 will cause the tappet 242 similarly to operate the lever 202 and eject a sole from the slot 52. Upon the next partial rotation of the shaft the tappet 243 will eject a sole from the slot 53, and upon the next partial rotation of the shaft the tappet 244 will eject a sole from the slot 54. Then upon the next partial rotation of the shaft the opposite end 241' of the tappet 241 will come into action at the slot 51 and soles will be ejected successively in the named order by the opposite ends 242', 243', 244' of the tappets as they are brought into action by rotation of the shaft 224.

The ratchet wheel 232 is turned one tooth at each indexing of the main turret of the eight-station machine by mechanism shown in Fig. 3. Mounted on the main turret 250 (Fig. 1) in a manner to be described is a series of cam blocks 251, 252, 253, 251', 252', 253', 254' one for each pad box of the machine. In Fig. 4 one of these cam blocks 254' has just been moved in a leftward direction by rotation of the turret 250, the inclined upper face of the cam 254' has engaged a roll 256 on a lever 258 pivoted at 260 to the shelf 24, lifted the lever and caused a pawl 262 pivoted at 264 on the lever to rise, engage a tooth of the ratchet wheel 232 and rotate the wheel and the shaft 224 one-eighth of a turn, the parts being now in position to be operated by the next cam 251 of the series (Fig. 2) which will act upon the next indexing of the turret 250 to operate the pawl 262, in the manner described, to cause the tappet 241 to swing the lever 201 to eject a sole through the slot 51.

The pawl 262 is held by a compression spring 266 (Fig. 4) against a stop 268, and the throw of the lever 258 is adjusted by a stop screw 270 against which it rests by gravity.

The cam which operates the tappet 244 is not shown in Fig. 2 but would be half way between the cams 253 and 251'. The cams 251', 252', 253' and 254' which operate in a similar manner the opposite ends 241', 242', 243' and 244' of the tappets to eject the second series of four soles are clearly shown in Fig. 2.

Each of the eight cams 251, etc. (Figs. 2 and 4), is fixed to an upright 272 which has a cross-piece 274 (Fig. 4) formed at each end to engage the surface contour of one of the eight cylinders 12 with which the sole-attaching machine is pro-

vided, as disclosed in the Ballard et al. patent above referred to. The cross-piece 274 is clamped between two of the cylinders 12 by setscrews 276 and is held down by screws 278.

To turn the turntable 14 one-fifth of a revolution in timed relation to the ejection of soles, the cam on each upright 272 has a projection 280 (Fig. 3) on which is an upstanding roll 282 arranged to engage, when the turret turns, a notch 284 in a spider 286 secured to the hub 16 of the turntable 14.

In the position shown, the cam 253' is visible to the operator at the operating station and may, for his convenience, be permanently marked 1L, the next cam 254' marked 2R, cam 251 marked 3L, cam 252 marked 4R, cam 253 marked 1L again, and so on for the second series of four. This will indicate to the operator that the next pad to come along when he indexes the machine will be for a left shoe and that the sole therefor will be ejected from the first slot (51). When the mark 2R shows, he will know that a right shoe pad is coming along next and that the sole therefor will be ejected from the second slot (52). That is, the letter will indicate whether a left or a right shoe pad comes next, and the number will be that of the slot counting from left to right from which the next sole will be ejected.

It will be understood, as fully described in the Ballard et al. patent referred to above, that means for relatively locating a shoe and sole and for applying pressure to the shoe is provided at each of the eight "stations." These means comprise a pad box 290 in which is a pad 292 on which the sole is laid, gages 294 for locating the forepart of the sole and shoe, gages 296 for locating the rear part of the sole and shoe, and abutments 298, 300 for engaging respectively the forepart of the shoe and the cone of the last. The forepart gages 294 are controlled by a treadle 306 acting through a rod 308, and the gage for the rear part of the sole is operated by a handle 310. The operator now places a shoe on the sole, the forepart of the shoe being located by the shoe gages associated with the forepart sole gages. The operator then grasps a handle 312 and swings the toe abutment 298 and the last abutment 300 over the shoe, the toe abutment being adjusted lengthwise of the shoe by turning the handle 312. This swinging of the abutments over the shoe causes the rear gages 296 relatively to locate the heel ends of the shoe and sole. A treadle 314 is depressed, whereupon oil under pressure enters the cylinder 12 the piston of which acts through a system of levers to depress the abutments 298, 300 and press the shoe against the sole on the pad 292. A lever 316 is operated to cause indexing of the turret 250 to bring the next pad box 290 at the left of the operator into position at the operating station, that is, in front of the operator where he is standing.

If desired, the use of the gages may be dispensed with. The cement on the sole, having been activated by treatment in the cabinet as above described, is of course pressure-responsive. Therefore, the sole may be spotted on the shoe with sufficient accuracy by eye, the operator then placing the shoe and sole upon the pad and applying pressure in the manner described.

In starting the machine, the current for the heater 106 is turned on long enough beforehand to heat the apparatus so that the temperature of the vapor-laden air in the cabinet is about 68° to 70° C. (154° to 172° F.). This will not take

long since the well 104 contains only a relatively small quantity of water which surrounds the immersion heater 106. Above the well the water spreads out the full size of the cabinet to provide a large evaporating surface and is only deep enough to at least partially immerse the pipes 100 through the lower sides of which air is being forced. The air, as it bubbles up through the water, is heated and laden with water-vapor nearly to the saturation point; that is, it may have, for example, about 95% relative humidity. In passing up through and around the baffles 130, 126 and 122, any water as such will be removed and in passing around the baffle 122 the vapor-laden air will be mixed with air from the pipe 92 the quantity of which may be controlled by a valve 290 in the pipe 90. As a result, the relative humidity of the vapor-laden air in the chamber may be varied to the desired extent for treating soles in different conditions of temper as they come to the machine.

After the cabinet is heated, the operator places soles in the cabinet and shoes in the trays. Supposing, for example, the cam 253 (marked 'L' in Fig. 1) is visible, he places a left sole in the slot 51 of the cabinet and the shoe to which this sole is to be attached in the tray A. A right sole is then placed in the slot 52 and the shoe in the tray B. A left sole is placed in the slot 53 and a left shoe in the tray C. A right sole is placed in the slot 54 and a right shoe in the tray D.

After the first sole has been in the cabinet for about thirty seconds, the operator indexes the machine by operating the lever 316, bringing the cam 254 marked '2R' to the operating station. With his right hand he takes a shoe from the rack and puts it in the tray E which is now in the position D of the drawing. With his left hand he takes a sole for this shoe from the table and with his right hand removes the partially ejected sole from the slot 51 of the cabinet and inserts the new sole that is in his left hand. He places the ejected sole on the pad, closes the gages by depressing a treadle 306 connected to the rod 308 (Fig. 1), and takes the shoe from the tray A which is now at the position E of the drawing, places it upon the sole, applies pressure to the shoe and sole by depressing the treadle 314, and indexes the machine by operating the lever 316. This causes the second sole to be ejected from slot 52 and presents the shoe in tray B at the operating station. A new shoe is placed in the tray A, now at the right of the operator, and the sole therefor in slot 52 after removing the ejected sole in that slot. The sole taken from slot 52 is laid on the pad, and the shoe from tray B is attached to it, and so on. After all the eight stations are filled, the cam marked 'L' will again be visible at the operating station and the operator knows that the station to be presented by the next indexing movement will be the one with which he started. Accordingly, he indexes the machine and the first shoe treated is released as it arrives at the operating station. He removes the completed shoe, places it in the rack and takes a new left shoe from the rack, places it in the empty tray and takes a left sole from the table, removes the sole ejected from the slot 51, places the new left sole in its place, puts the ejected sole upon the pad and attaches it to the shoe presented by the tray 70 nearest this station, and so on.

Should it be desired to have the soles in the cabinet for a less time, the operator will first place soles in the slots 51, 52 and 53 and shoes in the trays A, B and C. Then, after the first

sole has been in the cabinet long enough to be activated, he places a new sole in the slot 54 and puts a shoe in tray D. He then indexes the machine, causing the sole to be ejected from the slot 51, which sole he attaches to the shoe in tray A and proceeds as before, introducing a new sole into the empty slot in the cabinet and attaching the ejected sole to a shoe.

Further improvements in apparatus of the type herein disclosed form the subject-matter of an application Serial No. 674,468, filed June 5, 1946, in my name.

Having thus described my invention, what I claim as new and desire to secure by Letters Patent of the United States is:

1. In a sole-attaching machine, a series of pressing devices arranged to be presented in turn at an operating station, a table adjacent to said station mounted for rotation in a horizontal plane, a cabinet adjacent to said station for treating soles, means operated by movement of the pressing devices for turning the table, and means for ejecting a sole from the cabinet.

2. In a sole-attaching machine, a turret carrying a plurality of shoe-pressing devices, a carrier for shoes, a cabinet for treating several soles at a time, means operated by turning of the turret for advancing the carrier, and means operated by movement of the turret for ejecting one of the soles from the cabinet.

3. In a sole-attaching machine, a plurality of shoe-pressing devices, means for moving said devices to present them in turn at an operating station, a carrier for shoes arranged when moved to present a shoe at the operating station, apparatus at the operating station for activating cement on the sole to be attached to a shoe on the carrier, means actuated by movement of the shoe-pressing devices for moving the carrier to present a shoe at the operating station, and means operated by movement of the pressing devices for causing a sole with activated cement thereon to be ejected from the activating apparatus.

4. In a sole-attaching machine, a turret, a plurality of presses carried by the turret and arranged by rotation of the turret to be presented in turn at an operating station, a carrier for shoes mounted on the turret, means on the turret to advance the carrier at each rotation of the turret to present the shoes thereon in turn at the operating station, a cabinet adjacent to the operating station for treating several soles at a time to activate cement thereon, an ejector for each sole, means for operating the ejectors in turn to eject an activated sole, and means adjacent to each press on the turret constructed and arranged to engage the ejector-operating means and cause a sole to be ejected at each partial rotation of the turret to present another press at the operating station.

5. In a sole-attaching machine, a turret, a plurality of pads on the turret arranged to be presented in turn at an operating station by rotation of the turret, a turntable mounted on the turret having a plurality of trays each to receive a shoe, a cabinet adjacent to the operating station for treating a plurality of soles at a time, means operated by rotation of the turret for turning the table to present shoes one at a time to the operator at the operating station, and means for ejecting soles one at a time from the cabinet.

6. In a sole-attaching machine, a plurality of presses arranged to be presented in turn at an operating station, a carrier for a plurality of shoes movable to present the shoes in turn at the oper-

ating station, a cabinet for containing a plurality of soles, means for heating the cabinet to activate cement on the soles, means operated by movement of the presses to move the carrier to present a shoe, and means operated by movement of the presses for ejecting a sole from the cabinet to be attached to the shoe presented by the carrier.

7. A sole-attaching machine having pressing devices mounted on a carrier which is advanced to present the presses in turn at an operating station, a cabinet for activating cement on soles, means for supporting the soles on edge in the cabinet, an ejector for each of the soles, levers for operating the ejectors, a shaft having tappets for engaging said levers one after the other, a ratchet for turning the shaft, and cams on the carrier for operating the ratchet to cause a sole to be ejected when the carrier is advanced to present another press at the operating station.

8. Apparatus for use in cement-attaching soles to shoes comprising a rotary carrier for presenting shoes one at a time at an operating station, a cabinet for treating several soles at a time to temper the soles and activate cement thereon, means for advancing the carrier step by step to present a shoe, and means for ejecting soles one at a time from the cabinet.

9. In a sole-attaching machine having a plurality of presses each presented in turn at an operating station for attachment of a sole to a shoe, a turntable adapted to carry a plurality of shoes, a device for activating cement on a plurality of soles, means operating as each press is presented at the operating station for ejecting an activated sole from the device, and means for turning the table to present a shoe adjacent to the operating station for attachment to the activated sole.

10. In a sole-attaching machine having a plurality of presses presented in turn at an operating station, a cabinet for containing a plurality of soles, means for heating the cabinet to activate cement on the soles, and automatic means for

ejecting one sole at a time from the cabinet for attachment to a shoe as each press is presented at the operating station.

5 11. In a sole-attaching machine having a plurality of presses, a cabinet for containing a plurality of soles, means for heating the cabinet to activate cement on the soles, and operator-controlled means for ejecting one sole at a time from the cabinet for attachment to a shoe by one of the presses.

15 12. In a multi-press sole-attaching machine having a rotating turret which is indexed to bring the presses successively to an operating station, a cabinet for treating a plurality of soles at one time, and means operated by indexing the turret for ejecting a sole from the cabinet.

20 13. In a sole-attaching machine having a plurality of pressing devices, a carrier movable to present the pressing devices successively at an operating station, an activating cabinet adjacent to the operating station adapted to contain a plurality of soles at one time, and means operated by the carrier for ejecting a sole from the cabinet as each pressing device is presented at the operating station.

25 HELGE GULBRANDSEN.
